UNITED STATES PATENT OFFICE.

JAMES E. HENRY, OF ASHLAND, WISCONSIN.

FLUE-BLOW-OUT DEVICE FOR BOILERS.

No. 853,360.

Specification of Letters Patent.

Patented May 14, 1907.

Application filed May 18, 1906. Serial No. 317,569.

To all whom it may concern:

Be it known that I, JAMES E. HENRY, a citizen of the United States, residing at Ashland, in the county of Ashland and State of Wisconsin, have invented certain new and useful Improvements in Flue-Blow-Out Devices for Boilers; and I do hereby declare the following to be a full, clear, and exact description of the invention, such as will enable others skilled in the art to which it pertains to make and use the same.

My invention has for its object to provide an improved steam blow-out device for cleaning boiler flues, and to this end it consists of the novel devices and combinations of devices hereinafter described and defined in the claims.

In the accompanying drawings which illustrate the invention, like characters indicate like parts throughout the several views.

Referring to the drawings, Figure 1 is a view partly in side elevation and partly in vertical section, showing my improved blow-out device applied in working position, some parts being broken away; and Fig. 2 is a transverse vertical section taken approximately on the line $x^2 x^3$ of Fig. 1.

The numeral 1 indicates a horizontal boiler having the usual flues 2; and the numeral 3 indicates the rear wall of the boiler setting.

In the upper portion of the wall 3 is a bearing sleeve 4, and working vertically through this bearing sleeve is a steam pipe 5 which, at its lower end, is provided with a horizontally extended nozzle pipe 6. The nozzle pipe 6 is provided with a plurality of forwardly turned discharge nozzles 7 that are located one in the vertical plane of each vertical row of flues 2 and terminate quite close to the adjacent ends of said flues. The steam pipe 5 works vertically through the lower end head bracket 8 of a yoke-like frame 9, the vertical prongs of which are parallel to each other. To the upper end of the pipe 5 is secured a guide head 10 that is mounted to slide upon the parallel prongs or legs of the frame 9.

Loosely journaled in the upper portion of the frame 9 is a small windlass drum 11 that is provided with a ratchet wheel 12, and to the shaft of which is secured an operating crank 13. On the drum 11 is wound a cable

14, the lower end of which is attached to the upper end of the vertically movable steam pipe 5. A retaining pawl 15 which, as shown, is pivoted on the upper portion of the frame 9, acts upon the ratchet wheel 12 to prevent rotation of the drum 11 under the weight of the pipe 5 and parts carried thereby.

For the purpose of blowing out the flues, steam would usually be conveyed from the boiler 1 to the vertically movable steam pipe 5 through a flexible pipe or hose 16. For the purpose of indicating with which horizontal row of flues the nozzle pipe 6 is vertically aligned, the sliding head 10 is provided with a pointer 17, and the adjacent leg of the frame 9 is provided with marks 18.

As is evident, the nozzle pipe 6 may be vertically adjusted, at will, by means of the windlass and crank, and thereby brought into such position that its nozzle 7 will be aligned with the flues of any horizontal row. Thus, simple and efficient means is afforded for rendering the flue blow-out device operative without entering or opening up the fire-box or combustion chamber. It is, therefore, possible to blow out the flues without extinguishing the fire and, hence, without loss of time or interruption in the use of the boiler. Furthermore, the device is simple and of small cost.

What I claim is:

The combination with a boiler 1 having flues 2, and a wall 3 joining one end of said boiler, of a steam pipe 5 working vertically through said wall 3 and provided, at its lower end, with a nozzle pipe 6 having nozzles 7 adapted to align with any of the horizontal rows of said flues, a relatively fixed rectangular frame 9, through a portion of which said pipe 5 is mounted to slide, a windlass on the upper portion of said frame, a cable connecting said windlass to said pipe 5 for moving the same vertically, and means for locking said windlass against rotation to support said pipe 5 and nozzle pipe 6 in different vertical positions, substantially as described.

In testimony whereof I affix my signature in presence of two witnesses:

JAMES E. HENRY.

Witnesses:

MARTIN A. KENNEDY,
HALE S. COLEMAN.
